ATTORNEYS

UNITED STATES PATENT OFFICE.

OSCAR LION, OF NEW YORK, N. Y.

FABRIC.

Application filed March 20, 1924. Serial No. 700,633.

To all whom it may concern:

Be it known that I, OSCAR LION, a citizen of the United States, and a resident of the city of New York, borough of Manhattan, in the county and State of New York, have invented a new and Improved Fabric, of which the following is a full, clear, and exact description.

This invention relates to fabrics and has 10 for an object to provide an improved fabric known on the market as chiffon and presents a structure having improved stiffening members at spaced intervals.

Another object of the invention is to provide a fabric of a chiffon type with sections 15 formed of a material adapted to absorb a greater quantity of finishing liquid than the other part so as to present a stiffer construction when dried.

20 In the accompanying drawing—

Figure 1 is a plan view of a small portion of a piece of fabric disclosing an embodiment of the invention.

25 Figure 2 is an enlarged fragmentary sectional view through Figure 1, approximately on line 2—2.

Figure 3 is a view similar to Figure 2 but showing the fabric before it is treated with a finishing liquid.

30 In producing chiffon to be used in forming bows for funeral bouquets and other similar purposes, a silk ribbon has been heretofore provided which is provided near its opposite edges with closer woven sections 35 in order to present a pleasing appearance and at the same time somewhat stiffen the article in order that it will remain in shape an appreciable time. As the flowers must be moistened from time to time, the ribbon 40 also becomes moistened and loses its shape.

In forming the ribbon, the same may be made in one continuous strip or may be made of any desired width and divided up into separate ribbons with tightly woven sections 45 on each side of each separate ribbon cut or torn from the original piece of fabric. In the present invention, the fabric is woven in the usual manner so as to provide a body 1 of fabric of usual construction and ornamental sections 2 on each side of the ribbon. Heretofore, the entire piece of chiffon was made from silk whereas in the construction shown in Figure 1, the body section 1 is made from silk while the various warp 50 threads 3 forming the principal part of the

sections 2, are formed from cotton. These cotton threads 3 are preferably of the same size as the warp threads 3' used in the section 1.

During the manufacture of the chiffon, it 60 may be made of a certain width as shown in Figure 1 or may be made in any desired width with the sections 2 distributed so that the finished piece of fabric may be cut or torn into strips or separate ribbons and each 65 strip or separate ribbon will appear as shown in Figure 1. Either before or after the fabric has been cut or torn into strips or separate ribbons, it is passed through a finishing 70 machine which applies finishing fluid thereto in order to give it the desired feel and the desired stiffness. Where all parts of the fabric are of silk, there will be an equal absorption of the finishing fluid but where the warp threads 3 of section 2 are formed 75 of cotton, there will be a greater absorption by these cotton threads.

When the fabric is dried after the finishing operation, the cotton warp threads 3 will be somewhat larger than the other warp 80 threads of the fabric as indicated in Figure 2, said extra size being caused by the extra amount of finishing fluid absorbed. This extra supply of finishing fluid will cause an extra stiffening of the sections 2 and will 85 results in causing the finished article to remain in the formation of a bow or other structure even though subjected somewhat to moisture by reason of the extra quantity of fluid in the threads 3. It is, of course, 90 evident that the ribbon could be made of any width and that the sections 2 could be made of any width and any number used without departing from the spirit of the invention.

95 What I claim is:

1. A strip of fabric formed with a plurality of stiffening sections, and a finishing fluid arranged thereon, said stiffening sections being formed of material capable of absorbing said finishing fluid to a greater 100 extent than the remaining material.

2. A piece of fabric formed with a body of silk and ornamental reinforcing means of material capable of absorbing finishing fluid to a greater extent than silk, and a coating 105 of finishing fluid arranged on the silk body and on the ornamental reinforcement.

3. A fabric, comprising a silk body, stiffening and reinforcing members of cotton, and a finishing fluid covering the entire fab- 110

ric, said members of cotton absorbing said finishing fluid to a greater extent than the silk body.

4. A fabric, comprising a silk body, reinforcing sections arranged on each side of the body formed of cotton, and a coating of finishing material arranged on the body and

the cotton reinforcing members, said finishing coating being of a material capable of being absorbed to a greater extent by cotton than by silk whereby the cotton reinforcing members will present a stiffer construction than the silk body. 10

OSCAR LION.
